(57) **CLAIM**

The ornamental design for a combined radio and power pole with pier, as shown and described.

DESCRIPTION

FIG. 1 is a front elevation view of a combined radio and power pole with pier, embodying my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is an isometric view thereof; and,

FIG. 8 is another isometric view thereof.

The combined radio and power pole with pier is shown with symbolic break in its length in the FIGS. 1-4 and FIGS. 7-8 drawing views. It is understood that patentability is based only on those portions of the article that are shown in solid lines, and the appearance of any portion of the article between the break lines forms no part of the claimed design. Portions of FIGS. 1 through 8 are shown in broken and dash-dot-dot lines illustrating portions of the article and environmental subject matter that form no part of the claimed design.
